UNITED STATES PATENT OFFICE.

LINUS G. READ, OF BRIDGEPORT, CONNECTICUT.

GOLF CLUB.

Application filed August 18, 1923. Serial No. 657,650.

To all whom it may concern:

Be it known that LINUS G. READ, a citizen of the United States, and resident of Bridgeport, in the county of Fairfield and State of Connecticut, has invented certain new and useful Improvements in Golf Clubs, of which the following is a specification.

The present invention relates to an improved golf club, and particularly that type 10 of club known as "woods," as distinguished from iron clubs. Woods are of three forms, the driver, the brassie, and the spoon, the variation being in the incline of the striking face; and of these three, the driver is 15 considered the most important, as the driver shot is supposed to be the longest and most essential to distance. While the invention will therefore be described more particularly with reference to drivers, it is intended to 20 comprehend the other wood clubs.

As those familiar with golf will realize, the tee shot taken with a driver, ought to be made with greater accuracy and more confidence than any other shot in the game, 25 because, on the tee, the player has his own choice of position and stance, and is free to tee the ball to suit himself. But the fact is, that the great majority of golfers not only find this their weakest shot, but have 30 less confidence in making it, than in making iron shots, where the lie is always more difficult.

This tremendous difference in proficiency 35 with the irons and woods, has been attributed to many causes, psychology being the common alibi, but I have found that the real reason lies in the design of the clubs, the wooden clubs, as heretofore made, embodying certain elements of design and construction which are opposed in principle to the work which the club is intended to perform. Principal of these elements, is the placing of the weight in the club head. The same laws which govern the action of other 40 moving bodies, govern the action of a driver head, when it moves at a velocity of about 200 feet per second, and if the weight is improperly placed a consequent turning or twisting of the club must necessarily result.

Golfers have accepted the "weight-behind-the-ball" rule, without realizing the very great error that if the weight is put behind the center line of the shaft, it is in the worst possible place, throwing the head, as it does, 50 entirely out of balance. The weight in the

usual driver is between one and two inches behind the center line of the shaft. It is behind the ball, but since it is also behind the center line of the shaft, its accumulated momentum forces the club head to turn 60 slightly, causing the face to tilt backwards and the heel to go forward, sending the ball away with not only a slice, but with a strong slicing spin and right hand roll.

The heaviest part of all moving bodies tries, with all the force of its accumulated momentum, to get in front, just as the head of an arrow always flies in front. If a stone is tied to a string and swung around the head, the heaviest portion will instantly 65 take the position furthest from you, and if it is tied so that the heaviest portion cannot take the outside position, then the heavy part will turn over to the front. Similarly, if a screw-eye is sunk into the 70 center of the top of a driver shaft, tying a string into the screw-eye, then swinging the driver around your head, the back of the driver head will instantly turn round to the front, and as it cannot stay in front, 75 it keeps turning the club, twisting the string, and this is precisely what it tries to do when it is swung at a golf ball. The natural result is a sliced drive, and the only possibility of hitting a straight ball is by holding the club tilted forward sufficiently to 80 neutralize the turning effect of the momentum.

A comparison of the balance of an iron club and the usual wood club by laying 85 them across a narrow table and letting the heads hang over the edge, will show that the face of the iron head will assume a vertical position, while the face of the wood head will tilt upward at an angle of about 90 thirty degrees. If a driver head cannot hang in a correct position, even at rest, it cannot be supposed that it will travel in a right position, when it is moving at high 95 velocity and with tremendous accumulation 100 of momentum.

To have the weight in the right place is just as essential in golf clubs as in hammers, axes, mallets and bats. Were the weight in a hammer as wrongly placed as in the driver, it would be practically impossible to drive a nail straight, and were an axe built on the same design, it would take the woodsman all day to hack down a single tree. Were a base-ball bat made with the weight 110

some two inches off the center line of the bat, there would be no such thing as a "home-run."

An object of my invention therefore, is 5 to provide a driver with the weight properly placed on the center line of the shaft, and so balanced that the center of gravity is as nearly as possible in the geometrical center of the head, so that the force applied to the shaft, or handle, and the accumulated momentum in consequence thereof, will flow uniformly through the entire area of the striking face, and will not tend to twist or distort the shaft at the moment 10 of impact.

A further object is to provide improved means for inserting and retaining the weight, so that it cannot become loose and fly out of its position, and to this end, I 20 propose to insert the weight from the bottom or sole of the head, and retain it by means of a removable sole plate. This construction furthermore facilitates altering of the weight to suit the desires of any player, 25 without in any way disfiguring the head.

A still further object is to provide a club, which will insure that the ball when struck will revolve upon a horizontal axis, that is to say, it will roll in a straight line forward; and to this end, I have extended the sole-plate of the striking face about one thirty-second of an inch, so that as the ball leaves the face of the club, and at which instant the face is rising and following the 30 ball, the ball will be given a foreward rolling impetus, causing it to revolve upon a horizontal axis, and causing it, therefore, when it strikes the ground to roll ahead, thus gaining in distance and also very 40 greatly gaining in accuracy.

I have also discovered that the area of the face of the present used wood club is deficient, and does not give the player equal opportunity of making a good hit with the 45 wood, as with his iron clubs, and it is another object of my invention, therefore, to provide a wood club of increased striking face area, approximately equal to that of the iron clubs; or in other words, approximately equal to the full area of the longitudinal section of the head.

I further propose to provide a striking face of improved shape. The shape of the face, as generally used, approximates a key-stone, being wide at the top and narrow at the bottom. If a ball is properly hit the point of contact should be nearer the sole than the top of the face, and this being so, the present shape does not give the player 55 the benefit of the wider area where it is most needed. Another object of my invention therefore, is to provide a striking face that is of practically the same, or of greater width, at the bottom, as at the top, and that 60 is of practically the same height at the heel

as at the toe; thus insuring that even though the body of the player may sway slightly forward or backward, causing the club head to engage the ball at a point slightly higher or lower, he will nevertheless, have a better 70 chance of making a good hit, the shape and area of the striking face being such that the full available area may be utilized.

Still another object is to provide, as one embodiment or modification of the invention, an improved "bulger" face club. The usual "bulger" or convex faced head, has its convexity extending from the heel to the toe of the striking area, or in other words, the center of the face bulges out from a vertical axis. The effect of this "bulge" is supposed to add to the length of flight of the ball, but at the same time it causes the ball to leave the face of the driver with a rotation on a vertical axis, spinning like a top, so to speak, and when it strikes the ground it, therefore, rolls off to one side or the other, depending upon whether the point of contact was to the right or to the left of the high point of the bulge. As this feature is admittedly bad, I propose to place the convexity as from the top to the bottom of the face, that is from a horizontal axis, so as to strike the ball in the same manner as a base-ball bat strikes a baseball. This will send the ball away rotating on a horizontal axis, rolling foreward instead of off to one side, thereby gaining both in distance and direction.

With the above and other objects in view, 100 embodiments of my invention are shown in the accompanying drawings, and these embodiments will be hereinafter more fully described with reference thereto, and the invention will be finally pointed out in the 105 claims.

In the drawings:

Fig. 1 is a perspective view of a wood driver, according to my invention;

Fig. 2 is an end or toe view of the same;

Fig. 3 is a bottom or sole view thereof;

Fig. 4 is a front or striking face view;

Fig. 5 is a longitudinal sectional view, taken along the line 5—5 of Fig. 3; and

Fig. 6 is a fragmentary end view of a 115 modified form, having a "bulger" face, according to my invention.

Similar reference characters indicate corresponding parts throughout the several figures of the drawings.

Referring to the drawings, the shaft 10, of hickory, steel, or other suitable material, has a wooden head 11, of persimmon, or other suitable wood, attached thereto, its neck 12 being secured to the shaft end by a cord winding 13, in the usual manner.

The weight is applied to the head by drilling a hole 14 from the sole directly along the center line of the shaft, and pouring hot lead 15 into it, the lead, when 130

cooled, being retained by means of a sole-plate 16 secured by screws 17. The hole may furthermore be bulged, as at 18, to insure against shifting of the weight, and 5 to give added weight at the center and directly behind the striking point of the face. With this construction the weight is placed substantially in the geometrical center of the head, is directly behind the 10 striking face, and is not behind the shaft, but along its center line. The club is perfectly balanced, and by the test of laying the shaft on a narrow table, with the head hanging free, the striking face will assume 15 a vertical position. In striking a ball the tremendous velocity and accumulated momentum will not tend to twist or distort the head, and the striking face will impact with the ball squarely and with full effect.

20 The weight may be conveniently altered, without marring the exterior finish of the head, by removing the sole-plate and increasing or decreasing the total weight by drilling out some of the lead, or adding 25 more, as desired.

The striking face 19 is of an area substantially equal to the longitudinal section of the head, and approximates the area of the usual iron club head. Its shape is 30 such that it is of substantially equal height at the heel as at the toe, so that the player will have the benefit of the full area in striking the ball.

As shown more clearly in Fig. 2, the 35 sole-plate 16 is projected slightly, as at 20, about one thirty-second of an inch, and is adapted as the head leaves the ball to impart a rotating impetus to the ball, so that it rolls about a horizontal axis. This 40 not only tends to straighten and lengthen the flight of the ball, but to cause it to roll straight ahead upon striking the ground, thus gaining in distance and direction.

45 In Fig. 6 I have illustrated a modification, in which a "bulger" striking face 21 is provided, the bulge being about a hori-

zontal center line, as distinguished from about a vertical line, as heretofore. With this form the ball will be given a horizontal 50 spin similar to that imparted to a base ball when struck by a bat, with the result that both the flight and roll of the ball will be in a straight line.

I have illustrated and described preferred 55 and satisfactory embodiments of my invention, but it will be obvious that changes may be made therein, within the spirit and scope thereof, as defined in the appended claims.

Having thus described my invention, what I claim and desire to secure by Letters Patent is:

1. In a golf club, a shaft, a head of wood or the like secured to the end of said shaft 65 and having a striking face, and solid weight means embedded in said head disposed rearwardly of said striking face, extending inwardly from the sole with its axis coincident with the central plane of 70 said shaft, and is substantially an approximate line of the axis of said shaft, to form a balanced head.

2. In a golf club, a shaft, a head of wood or the like secured to the end of said shaft 75 and having a striking face and a circular cross-section hole rearwardly of said striking face extending inwardly from the sole with its axis coincident with the central plane of said shaft, and having a bulged 80 portion intermediate its ends, and solid weight means inserted in and filling said hole, extending into said bulged portion to lock the weight means against movement, and substantially equally distributed 85 in all directions at right angles to the axis of said hole, to form a balanced head.

Signed at Bridgeport in the county of Fairfield and State of Connecticut this 1st day of Aug. A. D., 1923.
